UNITED STATES PATENT OFFICE.

HENRY C. EGERTON, OF RIDGEWOOD, NEW JERSEY, ASSIGNOR TO WESTERN ELECTRIC COMPANY, OF NEW YORK, N. Y., A CORPORATION OF ILLINOIS.

LOUD-SPEAKING RECEIVER.

1,161,639.

Specification of Letters Patent. Patented Nov. 23, 1915.

Application filed October 12, 1911. Serial No. 654,389.

To all whom it may concern:

Be it known that J. HENRY C. EGERTON, a citizen of the United States, residing at Ridgewood, in the county of Bergen and State of New Jersey, have invented a certain new and useful Improvement in Loud-Speaking Receivers, of which the following is a full, clear, concise, and exact description.

This invention relates to telephone receivers and has for its object the production of a compact and efficient receiver of what is termed the loud speaking type or one which will clearly reproduce sounds to make them audible and intelligible to one in the same room with such a receiver or within any reasonable distance thereof.

This invention relates more particularly to a type of receiver making use of a solenoid coil in place of a bobbin, the solenoid coil acting to vary the intensity of the attraction between pairs of juxtaposed magnetic pole pieces located in the solenoid.

Two of the pole pieces are movable and are attached to a pivoted arm connected with a diaphragma.

One of the features of this invention relates to means of supporting the pivoted arm in such manner that it is free from all unnecessary weight and friction, thereby rendering it more sensitive to the variations of current through the solenoid windings. This is accomplished by providing the arm with knife edge bearing members located between the pole pieces, providing a supporting or suspending block with notches with which said knife edges engage, and suspending the arm with the knife edges in engagement with said notches by means of a single suspending means consisting of a fine wire extending loosely through a hole in a projection of said arm which is in line with the pivotal points of the knife edges.

Another feature of this invention relates to the arrangement of apparatus and form of casing whereby the parts may be assembled into a compact structure and entirely inclosed to protect them from the weather and meddling hands.

Other features of this invention are the details of construction such as the mounting and adjusting of the parts.

In the drawings, Figure 1 is a perspective of the casing and horn; Fig. 2 is a plan view with the cover and horn supporting

plate removed; Fig. 3 is a perspective showing in detail the diaphragm arm and means of supporting it; Fig. 4 is a vertical sectional view with parts broken away; Fig. 5 is a detail sectional view of one of the solenoids; and Fig. 6 is a detail sectional view through both the solenoids taken on a plane at right angles to the section 5.

In the drawings 5 designates a casing which is generally rectangular in shape and is formed of cast brass or other suitable material. The end walls are sloped upwardly and there is formed integrally with the wider of the side walls a chambered portion 6 which opens into the interior of the casing 5. The chambered portion 6 is circular in shape and is adapted to receive a diaphragm 7 as will more fully appear. Formed integrally with the casing 5 and extending at right angles thereto are two posts 8, 8 adapted to support a mounting plate 10 which is secured thereto by means of screws 11, 11.

Secured to the mounting plate 10 are two solenoids 12, 12 each comprising an insulating spool 13, a brass shell 14 and magnetizing winding 15. These solenoids are secured to the plate 10 by means of screws 16, 16 passing through countersunk openings in said plate and engaging threaded bushings 17, 17 embedded in the spool head. Passing through the mounting plate 10 and the brass shell 14 is an adjustable core 20, said core being provided on its outer end with screw threads engaging screw-threaded openings in said plate and having a lock-nut 21 applied to its outer end.

Secured to the lower face of the mounting plate 10 between the posts is a wedge shaped block 25 having its inner or smaller end projecting forward between the solenoids 12, 12. The lower face of said block 25 is provided with V-shaped notches 27, 27 midway between the solenoids 12, 12 adapted to receive knife edges of pivoted members 28, 28, secured to a soft iron armature 30. Formed integrally with the soft iron armature 30 is a supporting member 31 which extends upwardly into a notch 32 in said mounting block and is provided with a hole 33 therethrough, the lower edge of which is in a line with the points of the V-shaped notches when the knife edges of the members 28, 28 are bearing therein and with the solenoids 12, 12 and in the same plane as the dia-

phragm 7. Extending through the hole 33 is a wire or other suitable suspending member 34 which is supported upon a tension member 35 secured to the supporting block 25. Secured to the armature 30 at equal distances on each side of the member 31 are two cores 37, 37 which extend into the brass shells of the solenoids in juxtaposition to the adjustable cores 20, 20. The upper ends 10 of the cords 37, 37 are in a straight line with and in substantially the same plane as the diaphragm 7 and the pivotal points of the armature 30. Attached to the armature 30 is a hardened steel extension 38 which projects from the casing 5 into the circular chamber 6 and is there attached to the diaphragm 7. The pivot members 28, 28, cores 37, 37 and extension 38 are secured to the armature 30 preferably by welding. Obviously this manner of mounting the armature 30 removes all unnecessary weight from the diaphragm, maintains it substantially balanced and provides a pivotal support of the least possible friction. The tensioning member 35 tends always to hold the pivotal members 28 in the notches provided therefor and compensates for any wear which may take place in the engaging parts. The advantage of having the pivotal point 20 of the armature 30, the lower ends of the cores 37, 37 to which the moving force is applied, and the diaphragm 7 which takes its movement from the movement of the armature, in substantially the same plane and 30 the same straight line is that with the very slight movement of the armature 30 the force is applied directly to the diaphragm 7 in substantially a straight line movement. The result of this is that practically the 40 whole of the applied force is utilized by moving the diaphragm to reproduce sound in accordance with the current changes to the electromagnets and lateral or resultant forces tending to warp or produce unnatural movements in the diaphragm are minimized. 45

A permanent magnet 40 of the conventional U or horseshoe shape has one of its legs secured to the upper face of the mounting plate 10 by means of screws 41, 41, the 50 other of said legs being extended under the armature 30 and being unsecured. The reason that the lower leg is not secured is that it has been found to give as good results when free and furthermore allows for a 55 certain amount of warping of the magnet without interfering with the adjustment of the parts. A portion of the casing 5 is depressed as shown at 45 to conform to the lower leg of said magnet 40.

The end of the armature extension 38 is 60 bent at right angles to the body of the extension and is provided with a screw-threaded aperture adapted to receive a screw 46 by means of which said extension and the diaphragm 7 are clamped together. The

diaphragm is seated upon a ring 47 formed of rubber tubing and has a second ring of the same material clamped against its opposite side by means of a face plate 48 which is secured to the wall of the chamber 6 70 and is provided with a horn supporting arm 49. The face plate 48 is secured to the wall of the chamber 6 by means of machine screws 50, 50 entering from the back of the casing. The casing 5 is provided with an 75 inwardly projecting flange portion 51 adapted to support a cover 52 which is secured thereto by means of screws entering from the back. A strip 53 of felt or rubber may be clamped between the cover 52 and the 80 flange 51 to make the structure air or water tight. When mounted for use the device is secured to the wall in the position shown in Fig. 1, and the assembling screws are inaccessible except when the receiver is removed 85 from the wall. The back face of the casing 5 is provided with a depression 58 in which is mounted a terminal block 59 supporting terminals 60, 60 to which the terminals of the solenoids 12, 12 are attached. By balancing the armature so that the weight thereof is removed from the diaphragm there will be no damping effect upon said diaphragm due to the armature lever. The lever operatively connecting the diaphragm 90 with the electro-magnets being a multiplying one, the device may be worked with a very small air gap and a consequently 95 larger efficiency. Furthermore, since the operative lever for the diaphragm is a multiplying one and has a pivotal point substantially in alignment with the two electromagnets, extraneous jars or vibrations 100 will have but little disturbing effect upon the balance of the instrument. 105

I claim—

1. In a telephone receiver, the combination with a diaphragm, an armature connected therewith, solenoids for operating said armature, a supporting block, pivotal members on said armature engaging said supporting block, a suspending member attached to said armature, and a tension spring carried by said block to which said suspending member is also attached. 110

2. In a telephone receiver, the combination with a diaphragm, an armature connected therewith, solenoids for operating said armature, a supporting block having V-shaped notches therein, knife edge pivotal members carried by said armature, a supporting member carried by said armature and having an opening therein in line with the knife edges of said pivotal members, and a suspending member passing 120 through said opening.

3. In a telephone receiver, the combination with a casing, of mounting posts in said casing, a mounting plate carried by said posts, solenoids supported by said 130

plate, an armature for said solenoids supported by said plate and a diaphragm with which said armature is connected.

4. In a telephone receiver, the combination with a casing, of mounting posts formed integrally therewith, a plate of magnetic material secured to said posts, solenoids secured to the inner face of said plate, an armature for said solenoids, and a supporting block for said armature, secured to the lower face of said plate and extending between said solenoids.

5. In a telephone receiver, the combination with a diaphragm, an armature con-

nected therewith, solenoids for operating 15 said armature, a supporting plate for said solenoids, and a U-shaped permanent magnet having one end attached to said plate and its other end free and in juxtaposition to said armature.

In witness whereof, I hereunto subscribe my name this 11th day of October A. D., 1911.

HENRY C. EGERTON.
